Application filed October 10, 1890. Serial No. 367,639. Term of patent 3½ years.

To all whom it may concern:

Be it known that I, PAUL PIGNOT, a citizen of the United States, residing at Hastings, Westchester county, New York, have invented 5 a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying drawing is a face view 15 of a carpet showing my new design.

My design consists of the body A and the border B. The body A contains a large panel filled with various flower and leaf forms and surrounded by flower and leaf forms and ornamental lines and figures. The border B

has an inner margin of irregular ornaments, a middle portion containing various groups of flower and leaf forms and ornamental lines and figures, and an outer margin containing several somewhat fan-shaped figures and conventionalized leaf forms. 25

What I claim as new, and desire to secure by Letters Patent, is—

1. The design for carpets, consisting of the body A, substantially as shown. 30
2. The design for carpet, the border B, substantially as shown.
3. The design for carpets, consisting of the body A and the border B, substantially as shown.
